M. SETTER.
TELEPHONE RECEIVER.
APPLICATION FILED MAR. 12, 1906.

Patented Dec. 23, 1913.

UNITED STATES PATENT OFFICE.

MICHAEL SETTER, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

TELEPHONE-RECEIVER.

1,082,289.

Specification of Letters Patent. Patented Dec. 23, 1913.

Application filed March 12, 1906. Serial No. 305,470.

To all whom it may concern:

Be it known that I, MICHAEL SETTER, a citizen of the United States of America, and resident of Chicago, Cook county, Illinois, have invented a certain new and useful Improvement in Telephone- Receivers, of which the following is a specification.

My invention relates to telephone receivers of that particular type in which the 10 electro-magnet cores are mounted in the cup to which the permanent magnet is secured, and upon the perimeter of which both the casing and the diaphragm are clamped and firmly held in place by the usual screw-threaded cap or centrally apertured cover.

Generally stated, the object of my invention is the provision of an improved and highly efficient telephone receiver.

Special objects of my invention are to 20 provide improved connections between the cord and the magnet-coils, to provide an improved arrangement for connecting the cores or pole-pieces with the cup and permanent magnet, and to provide certain details and 25 features of improvement tending to increase the general efficiency and serviceability of a receiver of this particular character.

To the foregoing and other useful ends, my invention consists in matters hereinafter 30 set forth and claimed.

In the accompanying drawings, Figure 1 is a longitudinal section of a telephone receiver embodying the principles of my invention, showing the rear end of the permanent 35 magnet in elevation. Fig. 2 is a longitudinal section of the same on a line at right-angles to the section in which Fig. 1 is taken, and showing the magnets in side elevation, a portion of the permanent magnet 40 being broken away to bring into view the stem or shank of the cup. Fig. 3 is a detail perspective view of one of the electro-magnet coils and its core or pole-piece. Fig. 4 is a face view of the cup with the electro-magnet 45 coils and pole-pieces in place. Fig. 5 is a detail view showing one of the electrical connections taken apart. Fig. 6 is a detail perspective of the cup and its integral stem or shank. Fig. 7 is a detail side elevation 50 or face view of one of the electrical connections, showing adjacent portions of the permanent magnet and the cup. Fig. 8 is a detail sectional view showing the method of mounting the core or pole-pieces on the stem or shank of the cup.

As thus illustrated, my receiver comprises the usual casing A of rubber or other suitable material, and the screw-threaded cap or centrally apertured cover B, which latter may also consist of hard rubber or other 60 suitable insulating material. The cup C has a rim or perimeter c connected with the bottom wall c¹ by means of side portions c², thus leaving gaps or openings c³ at the sides of the cup. The stem or shank c⁴ is cast integral with the said cup, extends rearwardly from the bottom thereof, and is provided with a couple of flat seats or faces c⁵, and also with a couple of transverse openings c⁶ and c⁷, each opening having a longitudinal 70 rib or projection c⁸. It will also be seen that the said stem or shank is provided with a transverse opening c⁹ which extends at right-angles to the openings c⁶ and c⁷. Furthermore, the said stem or shank is provided at each side and in its flat seats or faces with sockets c¹⁰. Openings or slots c¹¹ are provided in the bottom of the cup, adjacent to the flat seats or faces c⁵, and also round openings or holes c¹². With this 75 arrangement, the flat cores or pole-pieces D are provided with coils d and adapted to have their integral lugs or projections d¹ held in engagement with the sockets c¹⁰, as shown more clearly in Fig. 8. It will be 80 seen that these cores or pole-pieces are provided with round openings or holes d² adapted to register with the opening c⁹ in the stem or shank of the cup. After the cores or pole-pieces are assembled in place, 85 the poles of the permanent magnet E are then clamped flatwise upon the said cores or pole-pieces by a bolt F of brass or other suitable material. For this purpose it will be seen that the said permanent magnet has 90 its ends or poles provided with openings adapted to register with the openings d² and c⁹, as shown more clearly in Fig. 1. It will be understood that the said cup and its integral stem or shank are cast of Franklin 95 metal or other suitable non-magnetic material, whereby the magnetic lines of force are not short-circuited between the pole-pieces of the magnet.

The perimeter or rim c of the cup is 105 clamped between the sleeve or casing A and the cap B, as shown in the drawings, thus preventing the inner structure of the receiver from shifting relatively to the outside or casing. The opening c⁹ is provided with 110

a rubber bushing G and the opening c^7 is provided with a similar bushing H. The flexible cord I containing the usual conductors passes through an opening in the rear 5 of the casing and is tied on the hub or cross-piece e of the permanent magnet. The terminals i are then led downwardly and disposed at opposite sides of the stem or shank of the cup, as shown more clearly in Fig. 2. 10 The electromagnet coil terminals J are also extended upwardly at each side of the structure, passing through the openings c^{12} , as shown in the drawings. Each terminal J has a couple of screw openings j and j^1 , the 15 end of the terminal being provided with cheeks or side flanges j^2 , as shown in Fig. 5. A strip of rubber or other suitable insulation K is applied flatwise to each side of the stem or shank of the cup. The terminals or conductors J are then laid upon the outer surfaces of these strips of insulation, and the terminals i then adjusted in place between the flanges j^2 , at each side of the structure. Screws L are then inserted 20 into the bushing G for the purpose of holding the terminals i in contact with the terminals J, so as to complete the circuit of the receiver. Screws M are inserted in the bushing H for the purpose of securing the terminals J and the insulated strips K to the 25 stem or shank of the cup. In this way the cores or pole-pieces of the electro-magnet coils can be first inserted through the openings c^{11} , and the terminals J can then be secured in place, in the manner shown. After this the permanent magnet can be secured in place upon the stem or shank of the cup, substantially in the manner shown and described. The cord can then be tied to the 30 end of the permanent magnet, and its terminals i electrically connected with the terminals J, in the manner shown and described. After this the cord can be threaded through the casing, so as to permit the latter 35 to slide over the magnet structure. The diaphragm N can then be applied to the edge or perimeter of the cup, and then the cap B can be screwed upon the casing for the purpose of firmly clamping the cup and 40 diaphragm between its inner face and the edge or perimeter of the casing. In this way the structure is all rigidly and firmly connected in such manner as to permit the parts to be readily removed or inspected to permit 45 repairing and cleaning.

With the provision of the lugs d^1 , which can be formed by a partial punching operation, as shown in Fig. 8, it is evident that the cores or pole-pieces D will be held firmly 50 in place upon the stem or shank which is cast integral with the cup, thus preserving at all times the proper distance between the diaphragm and the poles of the magnet. The ribs or projections c^8 prevent the rubber bushings from turning when the screws 55

L and M are inserted for the purpose of completing and holding the connections in place.

It will be seen that the flanges X at each side of the stem or shank c^4 engage the edges of the pole-pieces D, thus further serving to prevent displacement of the latter. When the ends of the permanent magnet E are placed over the pole-pieces, the latter are practically secured in place and cannot be 70 disarranged, this being true even before the bolt F is inserted. It will be seen that the openings c^{11} are large enough to permit lateral or sidewise movement of the pole-pieces D, which motion is necessary in order 75 to insert and release the said pole-pieces.

What I claim as my invention is:—

1. In a telephone receiver, a cup formed with an integral bottom provided with a stem or shank having sockets and an opening, electro-magnet cores or pole-pieces provided with integral lugs adapted to engage said sockets, and each provided with an opening adapted to register with the opening in the said stem or shank, the bottom of 90 said cup having openings permitting lateral movement of said pole-pieces, a magnet having openings adapted to register with said other openings, a transverse bolt of non-magnetic material extending through said 95 openings to clamp the magnet and pole-pieces and stem or shank tightly together, with the said pole-pieces and stem or shank inside of said magnet, a diaphragm, and means for clamping the diaphragm upon the 100 rim or outer edge of said cup.

2. In a telephone receiver, a cup made of non-magnetic material and having a bottom provided with an integral stem or shank, electro-magnet cores or pole-pieces extending through the bottom of said cup and provided with integral lugs or projections suitably engaging the outside of said stem or shank, the bottom of said cup having openings permitting lateral movement of said 110 pole-pieces, a permanent magnet, means for binding the permanent magnet and electro-magnet cores and the said stem or shank tightly together, with the said stem or shank between the poles of the permanent magnet, 115 circuit connections secured to and insulated from the said stem or shank, a diaphragm, and means for clamping the diaphragm upon the rim or outer edge of said cup.

3. In a telephone receiver, the combination 120 of a cup provided with a bottom formed with an integral stem or shank having sockets and flat outer seats or faces, flat electro-magnet cores or pole-pieces provided with integral projections adapted to engage said 125 sockets, a permanent magnet, a single bolt extending transversely through and clamping the permanent magnet and pole-pieces and stem or shank tightly together, with the said pole-pieces and stem or shank inside of 130

said magnet, a cord tied to the rear end of the permanent magnet, magnet-coil terminals secured in place and electrically connected with terminals of said cord, and a 5 diaphragm, casing and cap, all constructed and organized substantially as and for the purpose set forth.

4. In a telephone receiver, a non-magnetic metal member, electro-magnet cores or pole-10 pieces provided with inner lateral projections adapted to be suitably engaged by the outer sides of said non-magnetic member to prevent relative displacement, said member having openings permitting lateral movement of the pole-pieces, means for clamping 15 the said pole-pieces and non-magnetic member together, with the pole-pieces outside of the non-magnetic member, and a diaphragm secured to said non-magnetic member and 20 disposed in proper relation to said electro-magnet cores or pole-pieces.

5. In a telephone receiver, a non-magnetic member, a diaphragm secured thereto, said member having a plurality of sockets at each 25 outer side thereof, a pair of electro-magnet cores or pole-pieces provided with inner lateral projections adapted to engage said sockets, said member having openings permitting lateral movement of the pole-pieces, 30 and means for securing the non-magnetic member and electro-magnet cores or pole-pieces tightly together, with the pole-pieces outside of the non-magnetic member, whereby the ends of said cores or pole-pieces are 35 retained at the proper distance from said diaphragm.

6. A telephone receiver comprising a cup having a stem, pole-pieces bearing against the outer sides of said stem, a magnet having portions lying outside of said pole-pieces, 40 a single bolt extending through the magnet and stem and pole-pieces, means on the stem and pole-pieces for preventing displacement of the latter, the bottom of said cup having openings permitting lateral movement of 45 said pole-pieces relative to each other, windings on said pole-pieces, and a diaphragm.

7. A telephone receiver comprising a magnet structure, pole-pieces, a single bolt extending through the said structure and pole-50 pieces, means on said structure and pole-pieces for preventing displacement of the latter, the bottom of said cup having openings permitting lateral movement of said 55 pole-pieces relative to each other, windings on said pole-pieces, and a diaphragm.

8. In a receiver, a stem or shank, pole-pieces adapted to engage opposite sides of said stem or shank, means for preventing displacement of the pole-pieces on the said 60 stem or shank, means permitting lateral or sidewise motion of the pole-pieces relative to each other during insertion or removal thereof, and means for clamping the pole-pieces upon the said stem or shank. 65

Signed by me at Chicago, Cook county, Illinois, this 7th day of March, 1906.

MICHAEL SETTER.
